UNITED STATES PATENT OFFICE.

JAMES K. WHITE, OF SALINA, KANSAS.

GRAIN-SEPARATOR.

1,306,239.

Specification of Letters Patent. Patented June 10, 1919.

Application filed August 30, 1917. Serial No. 188,929.

To all whom it may concern:

Be it known that I, JAMES K. WHITE, a citizen of the United States, residing at Salina, in the county of Saline and State of 5 Kansas, have invented certain new and useful Improvements in Grain-Separators, of which the following is a specification.

My invention relates to grain separators and has for its object to provide a device in 10 which the grain is separated from the chaff and other light particles of matter by delivering the same in a stream of air into a member formed with a cavity, whereby the stream of air and stock is caused to have its 15 direction of movement quickly changed so that the heavier particles such as the grain will be precipitated out of the air stream while the lighter particles, such as the chaff, travel with it and are discharged out of the 20 machine. Another object is to arrange the movable parts so that the same may be conveniently driven from a single shaft mounted in the machine.

The full objects and advantages of my invention will appear in connection with the 25 detailed description thereof and are particularly pointed out in the claims.

In the drawings, illustrating the application of my invention in one form,—

30 Figure 1 is a vertical longitudinal sectional view of one form of my invention. Fig. 2 is a view similar to Fig. 1 of another form of the invention.

In the type of separator shown in Fig. 1, 35 a pair of longitudinal beams 10 and 11 are employed which form the principal frame work of the machine. Upon these beams are secured cross beams 12, 13 and 14 which carry at their centers boxes 15, 16 and 17 40 journaling a single longitudinal shaft 18 extending throughout the length of the machine. Upon one end of the frame members 10 and 11 is mounted a blower 19 which has a rotatable member 20 secured to shaft

45 18. The grain is first threshed by a toothed drum and concave or by any other suitable device, and the stock from the thresher which includes the chaff and any other matter to be separated from the grain is fed 50 into the blower 19 at the suction opening 22 thereof through a spout 21. The same is then discharged in a stream of air from the blower 19 through a spout 23 into the upper portion of a hollow deflector 24 which is 55 positioned about shaft 18 with its axis in

alinement therewith. This deflector is preferably cone shaped or made in the form of a cone turned toward the stream of air, but may be rounded or spherical or have any other shape which would receive and 60 sharply deflect the blast of air and material carried thereby. As will be noted the stock passes into the interior of the cone member 24 near the upper periphery at its base which causes the air to be forced into the 65 apex of the same and to have its direction of movement rapidly reversed, the air leaving the cone below its axis in a direction opposite to that in which it entered. This causes the grain to be precipitated against 70 the side of the cone and to be discharged from the bottom of the same by gravity, while the straw and chaff are carried along with the stream of air away from the cone above the grain. To aid in this separation 75 a sleeve 26 is employed which is secured to shaft 18 within cone member 24 and is provided with a plurality of radial fingers 27, which beat and stir up the stream of stock and air causing the heavy particles to more 80 readily pass out of the air stream and loosening any chaff which may cling to the grain.

Along the shaft 18 and in continuity with the cone 24, is mounted a casing 25 which 85 conducts the returning air stream with the chaff in it into the mouth 28 of a second blower 29 mounted on the frame members 10 and 11 at the other end of the machine. This blower has a rotatable element 30 90 95 which is also mounted on shaft 18 and discharges the air and chaff out of the device through a spout 31 as shown in Fig. 2 into any suitable kind of a receiver or into the open, if desired.

The lower portion of the casing 25 is formed open at 32 and in this opening is positioned a chaffer 33 of ordinary construction comprising sides 34 interconnected by inclined slats 36. This chaffer is given a 100 reciprocating motion in a direction parallel with the shaft 18, which tends to forward any chaff which drops down upon the same, toward the blower inlet 28 where it will be drawn in and discharged with the remainder 105 of the chaff. Any grain which falls upon the chaffer readily passes directly through it and upon a shaking shoe 35. This shoe comprises sides 37 which reach up nearly 110 to the sides 34 of chaffer 33 and which are

- connected on the bottom by cross pieces 38 which support a perforated metal screen 39. As the grain comes in contact with this screen the same immediately passes through 5 the perforations in it and upon a hopper 40 connected with a spout 41, while the last traces of chaff and straw which may have passed through chaffer 33 are discharged over the tail end of the shoe.
- 10 I have found that by agitating the cone member 24 that better results can be obtained. This can be done by securing the same to the sides 34 of the chaffer 33 and having it shake with said chaffer, or by employing separate shaker means as desired. The method of shaking said chaffer and shoe is explained as follows: The chaffer frame 34 and cone 24 are hung by a number of links 42 which are pivoted to them 15 and to the undersides of the two frame members 10 and 11. Similarly the shoe 35 is hung on links 43 also pivoted to said frame members. In back of the blower 29 are secured to frame members 10 and 11 a 20 pair of depending brackets 44 in which is journaled a rocking bar 45 which has mounted on it a bell crank 145 having three arms 46, 47 and 48. Two of these arms 47 and 48 are respectively connected 25 by links 49 and 50, to the sides 34 and 37 of the shaking members 33 and 35 so that as the bar 45 is rocked the chaffer 33 and shoe 35 are simultaneously shaken in opposite directions. The other arm 46 is connected by a link 51 to an eccentric 52 mounted on shaft 18, which, as said shaft rotates, oscillates the bar 45 and the bell crank 145 connected therewith, thereby imparting the desired motion to the chaffer and shoe.
- 30 Although the member 24 has been referred to as a cone member, it becomes evident that any device may be employed which is formed with a cavity adapted to quickly change the direction of movement 35 of the air stream and so effect a separation of the grain and lighter substances.
- 40 The form of the invention shown in Fig. 2 differs only in the location of the two blowers 19 and 29. In this case both of 45 these blowers are positioned adjacent each other at the end of the machine opposite the cone member 24, the blower 19 being reversed so that the feed of the stock into the machine occurs in the opposite direction. Here a feeding spout 53 is employed 55 which makes but a slight bend in directing the stock into the cone member 24 which eliminates the additional friction caused by the return bend shown in Fig. 1. However, 60 the return bend aids in causing the grain to be forced into the lower portion of the air stream, thus reducing the distance the same must travel within the cone before separation occurs.
- 65 The advantages of my invention are

manifest. The separator is extremely simple and gives a greater output for the size of machine and power consumed. The separation is very effective, removing all traces of straw and chaff.

70

I claim:

1. A separator for grain comprising a member having a cavity therein which converges toward a substantially closed end, threshing elements in said cavity and means for forcing a stream of air and stock into said cavity against said end so that the direction of said stream is rapidly changed forwardly and rearwardly to cause the heavier particles to be precipitated out of 80 the air stream.

75

2. A separator for grain comprising a member having a cavity therein substantially closed at one end, means for projecting a stream of air and stock into said cavity so that the direction of the same is rapidly changed to cause the heavier particles to be precipitated out of the air stream, and means for stirring up and beating the grain and chaff which enters the 90 cavity.

95

3. A separator for grain comprising a member having a conical cavity therein substantially closed at one end and means for projecting a stream of air and stock into the upper portion of said conical cavity so that the air is forced into the apex of the cone and caused to abruptly return whereby the heavier particles are precipitated out of the air stream, and a beater positioned within 100 the cone member and acting upon the grain as the same passes into and out of said cone member.

100

4. A separator for grain comprising a member having a cavity therein, substantially closed at one end, a longitudinal shaft extending through said member and the cavity therein, a blower mounted on said shaft for projecting a stream of air and stock into said cavity, and a beater positioned on said shaft and operable within 110 said cavity.

110

5. A separator for grain comprising a member having a cavity therein substantially closed at one end, a longitudinal shaft 115 extending through said member and the cavity therein, a blower mounted on said shaft for projecting a stream of air and stock into said cavity, a beater positioned on said shaft and operable within said cavity, and a second blower mounted on said shaft for withdrawing the air and chaff from the machine.

120

6. A separator for grain comprising a member having a cavity which converges toward a substantially closed end, threshing elements in said cavity, means for shaking said member, and means for forcing a stream of air and stock into the said cavity against said end so that the direction of 125

130

130

said stream is rapidly changed to cause the heavier particles to be precipitated out of the air stream.

7. A separator for grain comprising a member having a cavity which converges toward a substantially closed end, threshing elements in said cavity, a longitudinal shaft extending through said member and cavity, a blower mounted on said shaft for 10 projecting a stream of air and stock into

said cavity, and a second blower mounted on said shaft for withdrawing the air and chaff from the machine, said blowers being mounted adjacent each other at the end of the machine opposite the aforementioned member. 15

In testimony whereof I hereunto affix my signature.

JAMES K. WHITE.
